NORMAN B. KOOSER, OF SAN JOSE, CALIFORNIA.

AUTOMOBILE COMPARTMENT-LID SUPPORTS.

Application filed September 29, 1924. Serial No. 740,591.

In certain forms of motor cars, especially the coupé type of motor car, a rear compartment is provided in the body of the car to which entrance is effected through an opening normally closed by a vertically swinging door or lid. Since this compartment is in constant use for carrying tools, parcels, and packages of various kinds, it follows that the raising and lowering of the lid is of frequent occurrence.

Heretofore a pair of jointed arms pivoted at one end to the lid and at the other end to the body of the car have been provided for holding the lid in an open position. That method, however, necessitates opening the lid a certain fixed distance in order to render the jointed arms operative, and this wide opening of the lid is not always convenient or desirable especially when the lid is raised by a woman or child.

Furthermore there are many times when it is desirable to open the lid further than the jointed arms permit, and again it is sometimes desirable to secure the lid in a partially open position such as, for instance, when fruit, game or other perishable matter is being transported in the rear compartment of the car and some ventilation is desired.

Finally, in the construction now provided it is a comparatively frequent occurrence for the lid to drop on the head, arm or hand of the person operating it and cause a more or less serious injury. Also, serious injuries have been occasioned by the pinching of the fingers between the two parts of the jointed arm, the weight of the lid being so great in most cars as to cause the arms to cut through the flesh and badly lacerate the same.

It is, therefore, one object of the present invention to provide a means for automatically securing the vertically movable lid of the rear compartment of a motor car in any desired open position whereby to overcome the objections hereinbefore set forth.

It is another object of the invention to provide a device of the character indicated that will require the manual operation of a fastening device before the lid is permitted to be lowered.

It is also an object of the invention to provide a device of the character indicated that is simple in form and construction, econom-

ical to manufacture, positive in operation, and highly efficient in its practical application.

In the drawing:

Figure 1 is a side elevation of a device embodying my invention in operative position on a car.

Figure 2 is an enlarged side elevation of a portion of the device shown in Figure 1.

Figure 3 is a plan view of the parts shown in Figure 2.

Figure 4 is an enlarged end view of another portion of the device including the operating lever.

Figure 5 is a side elevation of the parts shown in Figure 4.

Referring more particularly to the drawing, I show at 1 an outline of a portion of the rear part of an automobile body of the coupé type, the lid being indicated at 2 and hinged to the body portion at 3.

In effecting my invention I provide a ratchet bar 4 pivotally connected at one end to the lid 2 as indicated at 5, the ratchet edge of the bar preferably being directed rearwardly of the car as shown.

At 6 I show a combination housing, guide and bearing member fixedly mounted upon the side of body 1 and provided with a vertical slot 7 through which the ratchet bar 4 passes, the rear edge 9 of the ratchet bar engaging the edge 8 of the guide member 6.

At 11 is a pin carried by member 6 and upon which is pivotally mounted a dog 10, the dog 10 engaging the ratchet edge of bar 4 and having an upwardly and rearwardly extending arm 12 as shown, the housing forming a support for the dog 10.

Pin 11 has a slot formed in its outer end into which is slipped the inner end of coiled spring 13 as shown at 14, this end being securely held by mutilating the end of the pin. The spring itself is mounted on pin 11 and its outer end is secured to arm 12 by a screw 15, the tendency of the spring being to throw the arm 12 forwardly in the direction indicated by the arrow, and the dog 10 into engagement with bar 4.

On the outer end of arm 12 is pivotally mounted an element 16 as at 17, this element having a hole formed therein at 18 to receive a wire 19, the said wire being secured

in position by set screw 20. This element may be fixed at any angle to arm 12 so that the pull of wire 19 will be straight and consequently bending and breaking of the wire is obviated.

The wire 19 passes through a conduit 21 to a pin 22 pivotally mounted on a link 23 which is in turn pivotally connected to a lever 24 mounted at 25 upon a bracket 26 10 mounted upon the exterior of the car in any suitable and convenient position.

It may now be readily seen that as the lid 2 is raised the bar 4 slides upwardly but is in constant contact with edge 8, the 15 point of the dog 10 clicking over the several ratchet teeth. If the lid is released at any point it is positively and securely held in that position through the positive engagement of the dog with the bar 4, and the positive engagement of bar 4 with edge 8.

To lower the lid, it is raised slightly and lever 24 moved in the direction indicated by the arrow, this action withdrawing dog 10 20 from bar 4. Upon releasing lever 24, the 25 spring 13 automatically throws the dog 10 forwardly to engage bar 4. This device

eliminates accidental closing of the lid with possible accidental injury to the operator.

It is to be understood that while I have herein shown and described one specific 30 embodiment of the invention, changes in form, construction, and method of operation may be made within the scope of the appended claim.

I claim:—

The combination with an automobile body having a vertically swinging lid hingedly mounted thereon, of an element mounted upon the inner side portion of the body and having a vertical slot formed therethrough, 40 a ratchet bar pivotally mounted upon the underside of the said lid and engaging said slot, a pin mounted on said element, a pawl mounted on the pin to engage said ratchet bar and carrying an upturned arm, a spring 45 mounted on said pin and engaging said arm whereby to normally throw said pawl into engagement with said ratchet bar, and means for disengaging the pawl from the ratchet bar against the tension of said 50 spring.

NORMAN B. KOOSER.
